OLIVER A. HORN AND WILLIAM P. HORN, OF ADDISON, NEW YORK.

Letters Patent No. 85,740, dated January 12, 1869; antedated January 2, 1869.

IMPROVEMENT IN GAUGES FOR CIRCULAR SAWS.

The Schedule referred to in these Letters Patent and making part of the same.

To all whom it may concern:

Be it known that we, OLIVER A. HORN and WILLIAM P. HORN, both of Addison, in the county of Steuben, and State of New York, have invented a new and useful Improvement in Log-Setting Gauges for Circular-Saw Mills, and we do hereby declare the following to be a full, clear, and exact description thereof, reference being had to the accompanying drawing, which is made a part of this specification.

The subject of our invention is a device for regulating the thickness of lumber, sawn by a circular saw, in a more positive and efficient manner than has heretofore been accomplished.

It consists of one or more knees or gauges, located on the bed-frame of the saw, adapted to be adjusted relatively to the saw, to vary the thickness of board produced, and to be folded to admit of the logs being rolled over them, in placing them on the frame. The log is set up to these by the ordinary head-blocks, or analogous arrangements, and the boards sawn therefrom at a uniform thickness, determined by the distance of the face of said knees from the saw, which distance, and the consequent thickness of board or other lumber produced, are indicated on a suitably-graduated scale on the guide-ways of said knees.

In the drawing—

Figure 1 represents a plan view of our improved log-setting device in position on the saw-frame, a portion only of which is shown.

Figure 2 is a front elevation, and

Figure 3, a side or end elevation thereof.

A may represent the bed-frame of the saw.

B, the circular saw, mounted on its arbor, B', in said frame.

C, the log-carriage way, and

D, the log-carriage of a circular-saw mill.

All of these parts may be of any approved construction and arrangement.

E represents a suitable bracket, attached to the side of said frame, by bolts e e, and forming, at E', a suitable dovetailed or other way for the reception of the sliding block F.

e e are perforated lugs on the under side of said way, for the reception of the screw-shaft G, by which said block F is adjusted, and which is provided with a suitable hand-wheel, G', by which to operate it, and held from longitudinal displacement by the shoulder g and nut g'.

The block F is provided, on its under side, with a nut, f, for the reception of the screw G, and on its upper side with perforated lugs, f' f', to which is hinged, by the rod H, the knee I, which is provided with matching perforated lugs, i, for its attachment.

The knee I is further provided with a stop or prop, i', to sustain it in its vertical position, and at its front edge with perforated lugs, i'' i'', for the reception of the attaching-pintle or shaft J of the friction-roller K, which composes its face.

A graduated scale, L, is provided on the upper surface of the guide-way E', to indicate the distance of the face of the knee from the saw, and the consequent thickness of lumber, the rear edge of the block F serving as the pointer.

Our improved knee or gauge, in connection with the ordinary grooved wheels or track of the log-carriage, serves to effectually prevent the saw running deeper into the log, in case the brackets or knees of the head-blocks should, by reason of wear or other imperfection, be capable of movement toward the side of the saw, which would cut a "belly" on the plank, as, with my provision, all movement of the log in that direction is prevented, and the head-blocks, or other similar arrangement, only employed to hold the log against it.

Having obtained the desired thickness of lumber, the gauges preserve it until changed, it being only necessary to move the log up against them, at each cut, which operation may readily be performed by one comparatively a novice, as no nicety of adjustment is required.

Having thus described our invention,

What we claim as new, and desire to secure by Letters Patent, is—

In a saw-mill, one or more adjustable hinged knees or gauges, arranged on the side of the saw opposite to the ordinary head-blocks, for the purpose of regulating the thickness of the material sawed, substantially as described.

To the above specification of our new and useful improvement in folding knees or gauges for setting logs, we have signed our hands, this 22d day of April, A. D. 1868.

O. A. HORN.
WM. P. HORN.
